UNITED STATES PATENT OFFICE.

LAWRENCE H. NICHOLS, OF KENMORE, OHIO.

BELT.

Application filed April 12, 1927. Serial No. 183,159.

This invention relates to a belt for garments, the general object of the invention being to form the belt of a plurality of inflated tubes which are placed side by side so as to provide a belt of attractive and novel appearance and one which will be comfortable to wear, owing to its resiliency.

Another object of the invention is to make the ends of the tubes flat so that they can be readily attached to a buckle and also to provide means for fastening the tubes together.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:

Figure 1 is a perspective view of the improved belt.

Figure 2 is a rear view of the buckle and showing the ends of the belt attached thereto.

Figure 3 is a section on line 3—3 of Figure 2.

Figure 4 is a section on line 4—4 of Figure 1.

As shown in these views, the belt is composed of a plurality of superimposed tubes 1 which are inflated and which have their ends flattened, as at 2, which not only tends to hold the air in the tubes, but also pro-

vides means whereby one end of the belt can be attached to a buckle 3 and the other end to a hook-shaped member 4 which is detachably connected with the buckle so as to hold the belt about the person of the user. The tubes are fastened together by bands 5 which are placed at intervals along the length of the belt.

From the foregoing it will be seen that I have provided a novel form of belt which is composed of a plurality of superimposed tubes which are inflated so that the belt will have an attractive and odd appearance and one which will give free movement to the body of the user owing to its resiliency.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:—

A belt of the class described comprising a plurality of resilient tubes placed one upon the other, the tubes being inflated and having their ends flattened and turned over to retain the air in the tubes, a belt buckle connected with the flattened ends at one end of the belt and a buckle engaging member connected with the flattened ends at the other end of the belt, said member and buckle acting to hold the flattened ends in flattened and turned-over condition.

In testimony whereof I affix my signature.

LAWRENCE H. NICHOLS.
